United States Patent Office.

W. S. COLWELL AND F. VEAZIE, OF PITTSBURG, PENNSYLVANIA.

Letters Patent No. 60,999, dated January 8, 1867.

IMPROVEMENT IN STAVE MACHINES.

U. S. Schedule referred to in these Letters Patent and making part of the same.

TO ALL WHOM IT MAY CONCERN:

Be it known that we, WILLIAM S. COLWELL and F. VEAZIE, of Pittsburg, in the county of Allegheny, and State of Pennsylvania, have invented a new and useful Improvement in "Stave-Sawing Machine;" and we do hereby declare the following to be a full and exact description thereof, reference being had to the accompanying drawings, and to the letters of reference marked thereon.

Our invention consists in the use of two saws travelling in opposite directions, and in the use of a feed-carriage provided with clamping jaws for holding the timber firm, said saws, carriage, clamping jaws, and the other parts connected therewith being constructed, arranged, and operating in the manner hereinafter described.

To enable others skilled in the art to make and use our invention, we will proceed to describe its construction and operation.

In the accompanying drawings, which form part of our specification—

Figure 1 represents a top view of our improved stave-sawing machine.

Figure 2 represents a front elevation of the same.

Figure 3 represents a side view of the feed-carriage of our improved stave-sawing machine.

Figure 4 represents an end view of our improved stave-sawing machine.

Figure 5 represents a side view of the rocking arm to which the saws are attached.

Figure 6 represents a perspective view of a part which we use for a foot-brace and journal bearing.

Figure 7 represents a perspective view of the guide we use for the guides of the clamping jaws.

Figure 8 represents the guides and supports of the clamping jaws.

Figure 9 represents a transverse section of the endless screw used for operating the clamping jaws *e* and *f*.

Figure 10 represents an end view of the ratchet-lever used for operating the clamping jaws *g* and *h*.

Figure 11 represents a side view of the ratchet-lever referred to in fig. 10.

In the drawings, in which similar letters and figures of reference refer to similar parts—

A' represents the frame of the machine, which frame may be made of wood or iron, or wood and iron combined. The manner and means of constructing the frame we leave to the judgment and skill of the mechanic. The frame *A'* is provided with a feed-carriage, *n*, which is provided with friction-wheels, *s* and *10*; the friction wheels *s* are provided with grooves, and run between two rails, *x* and *x'*. To the under side of the carriage *n* is attached rack *x*⁴, into which gears an endless screw, *x*¹ on the shaft *x*², (as indicated by dotted lines in fig. 2.) The bearings of the shaft *x*² are in the end of the frame *A'* and lever *22*, and so arranged that by raising said lever the endless screw will be thrown into gear with the rack *x*⁴, and by lowering the lever the endless screw is unshipped from the rack *x*⁴. On the upper side of the feed-carriage *n* are placed two guides *D* and *D'*, the form of which is clearly shown in fig. 7. In these guides are placed guides and supports for the clamping jaws *e*, *f*, *g*, and *h*; the form of these guides or supports is shown in fig. 8. They are provided with flanges, *20*, for holding and guiding them properly in the guides *D* and *D'*. The clamping jaws are placed in the opening *15*, (see fig. 8,) and part marked *16* is used for a bearing for shaft *P*, on the end of which are placed wheels, *30*, which gear into the racks *w* of the guides *D* and *D'*. The clamping jaw *e* is provided with a rack, *o'*, which gears into the endless screw *i*, which moves longitudinally on the shaft *11*, and is revolved with the shaft by means of what is termed a "feather," which is fitted in a groove in the shaft, which is also fitted to a groove made in the endless screw, as shown in fig. 9. The clamping jaw *f* is provided with an arm, *J*, on the end of which is a pin, *9*, which is fitted in a groove, *y*, in the endless screw *i*. By thus connecting the arm *J* of the clamping jaw *f* and the rack *o'* of the clamping jaw *e* with the endless screw *i*, the jaws *e* and *f* can be made to move towards or recede from each other in accordance with the motion given to the endless screw *i*; that is to say, by turning the endless screw in one direction the jaws will recede from each other, and by turning it in the opposite direction the jaws will move towards each other. The clamping jaw *h* is provided with a lever, *l*, on the end of which is a tongue, *8*; the position and form of this tongue on the end of the lever are clearly shown in fig. 10. The tongue *8* of the lever *l* gears into the rack *m* on the end of the arm *k* of the clamping jaw *g*. By thus connecting the lever *l* to the clamping jaw *h*, and gearing the tongue *8* of the lever *l* into the rack *m* on the end of the arm *k* of the clamping jaw *g*, the jaws *g* and *h* can be moved towards or from each other by moving the lever *l* in the desired direction for obtaining the motion desired of the jaws. On the end of the shaft *P* is

placed a lever, *u*, to which is attached a pawl, *t*, which is used in connection with the lever *u* for revolving the wheels 30, which are permanently secured on the shaft *P*. The pawl *t* is placed in between the cogs of the wheel next to the lever, and by operating the lever the wheels 30 and shaft *P* can be revolved, which will move the clamping jaws *g* and *h* towards or back from the saws *A* and *B*, in accordance with the way wheels 30 are turned. By this arrangement of the clamping jaws *g* and *h*, and the manner of moving them towards and from each other, and by the means for moving them towards the saws, timber of any size or form (suitable for staves) can be firmly held between the clamping jaws and sawed entirely up into staves. The shaft 17, which has its bearings in the parts marked 24 and *C*, is provided with pulleys, 21 and 26, and a disk, 7, to which is secured what is termed a compound or double crank, 4, to which are connected rods 5 and 6, which are attached to the lower ends of the saw arms 1 and 2. The saw arm 2 is permanently secured on the shaft 3, which has its bearings in the parts marked *o*. The saw arm 1 is loose, and is oscillated on the shaft 3. Motion is imparted to the feed-carriage *n* through the medium of the pulleys 21 and 28 and the belt *y'*. From the above description, and by reference to the accompanying drawings, the skillful mechanie will readily understand the construction and arrangement of the several parts of our improved stave-sawing machine, and the relation that these parts bear to each other. We will, therefore, proceed at once to describe its operation, which is as follows:

Having the timber cut into suitable lengths for staves, it is then placed between the clamping jaws *g* and *h*, and firmly secured by forcing the jaws against the ends of the timbers through the medium of the lever *l* and rack *m*. The timber is then brought in line with saws *A* and *B* for making the desired cut. The clamping jaws *e* and *f* are then forced up against the timber through the medium of the hand-wheel *R*, bevelled wheels 12 and 13, and the endless screw *i*; motion is then imparted to the shaft 13, which will impart motion to the saws *A* and *B* and to pulley 21, which, through the medium of belt *y'*, will impart motion to the shaft *x*², which will impart motion to the feed-carriage *n*, (when the endless screw *x*¹ is thrown in gear with the rack *x*⁴ on the under side of the carriage,) which will feed the timber up to the saws *A* and *B*, which will travel in opposite directions, and cut two staves at one operation.

Having thus described the nature, construction, and operation of our improvement, what we claim as our invention, is—

1. The arrangement of the saws *A* and *B*, arms 1 and 2, shaft 3, connecting-rods 5 and 6, and crank 4, when said arrangement is used for sawing out the concave and convex sides of a stave at one operation, as herein described.
2. The arrangement of the guides *D* and *D'*, clamps *e*, *f*, *g*, and *h*, (provided with arms *J* and *K*), rack *m*, lever *l*, endless screw *i*, and wheels 12 and 13, when said parts are arranged and operating as herein described and for the purpose set forth.
3. The arrangement of the racks *w*, wheels 30, shaft *P*, lever *u*, provided with pawl *t*, when said parts are used in connection with the clamps *e*, *f*, *g*, and *h*, as herein described and for the purpose set forth.

W. S. COLWELL,
F. VEAZIE.
